Patented Dec. 6, 1927.

UNITED STATES PATENT OFFICE.

LEWIS E. WEBSTER, OF WYOMING, PENNSYLVANIA, ASSIGNOR TO THE WYOMING SHOVEL WORKS, OF WYOMING, PENNSYLVANIA, A CORPORATION OF PENNSYLVANIA.

SHOVEL HANDLE.

Application filed June 9, 1925. Serial No. 35,856.

This invention relates to improvements in shovel handles and more particularly relates to improved fastening means for the wooden grip and sheet metal body portion of the grip and sheet metal body portion of the handle.

More particularly the present invention relates to improvements in the construction shown in my prior Patent No. 1,476,783, dated December 11, 1923.

One of the objects of the present construction resides in the provision of ferrules of novel form which are adapted to be fitted to and secured against relative rotation with respect to the wooden grip which is received thereby. The construction of the ferrule is such that the ferrule extends substantially over the top of the sheet metal arm portions of the shovel and is provided with a smooth curved configuration at this point. In this way the shovel handle is more acceptable to the user inasmuch as the ferrule affords protection to the hands of the user and prevents access to possible sharp or abrading edges of the arm portions.

The improved construction further provides means for transmitting bearing down forces directly vertically from the grip to the arm portions of the handle through the shouldered portion of the ferrule. Greater strength is provided to prevent twisting of the grip by reason of the socket in the ferrule being of larger dimensions. The cutting away of the interior portions of the arms by the horizontal slots previously utilized to receive the ferrules is obviated and the assembly is made correspondingly stronger. Furthermore the assembly operation to secure the grip assembly in place upon the arms is materially simplified and facilitated and the chances of improper assembly which occasionally occurred with the previous arrangements are obviated.

In the drawings,

Fig. 1 is an elevational view of my improved handle, certain parts being shown in section.

Fig. 2 is an end view of the top of the handle.

Fig. 3 is a detail sectional view taken on line 3-3 of Fig. 2.

In more detail the shovel handle includes arm portions generally designated 10 and comprising inner sheet metal portions 11,

an interior reenforcement element 12 and outer sheet metal portions 13 integral with portions 11 and folded over and embracing the interior reenforcement as shown in Fig. 3.

The wooden grip 14 is of the usual construction being suitably shaped at its ends to receive sheet metal ferrules generally designated 15. These ferrules are provided with struck-up portions or prongs 16, which enter the ends of the wooden grip and prevent relative rotation of the grip and ferrules. Any suitable number of these prongs may be provided. In the illustrated embodiment one prong on each ferrule is shown.

The shape of the ferrule and the shape and arrangement of the upper ends of the arm portions constitutes the novel feature of the present invention. As shown in Fig. 3 and to the right in Fig. 1 the ferrule 15 is provided with a curved boss or fillet 17 which is of such configuration that when the parts are assembled it projects over the upper ends of the portions 11 and reenforcement element 12. The boss is further provided with a turned in section forming a semi-circular socket portion 18 against which the upper ends of parts 11 and 12 abut when the handle is assembled. Depending below the semi-circumferential portion of the boss on the ferrule are straight boss portions 19 which are arranged to closely fit the outer edges 20 of the arm portions and thus prevent relative rotation of the ferrules and the arm portions of the handle. The entire assemblage of parts is secured together by the usual through rivet 21.

The assembly of the parts is effected in the following manner. The ferrules 15 are first driven on the ends of the wooden grip 14. The grip assembly is then placed above the arm portions and the vertical slots in the ferrule defined by boss portions 19 are aligned with the arms 10. The grip assembly is then forced down the ferrule sliding down inside the arms and parts 19 embracing the outer edges 20 of the arms. After the grip assembly is forced to its lowermost position with the socket 18 engaging the tops of the portions 11 and reenforcing element 12 the rivet 21 is placed in position and riveted to secure the parts together. When

the parts are thus assembled and extremely strong assembly is secured the flat parts or surfaces 22 of the ferrules abut against the flat inner surface of portions 11 of the arms.

5. Horizontal slotting of the arm portions 11 is obviated with the present construction. The ferrules not only provide a protection to the hands of the user against engagement or rubbing upon the upper ends or edges of parts 11 and 12 but also provide an extremely rugged construction for preventing the relative rotation of the grip assembly with respect to the arm portions. The semi-circular socket portion 18 is also particularly adapted to transmit vertical forces from the grip assembly to the arms. The rivet 21 is arranged to interengage and closely fit openings in the inner wall portion 12 which was previously cut away adjacent the rivet and also in the ferrules and in the reenforcing element as heretofore.

I claim—

1. An assembly for a shovel handle having a wooden grip portion and a pair of spaced arm portions comprising in combination with the aforesaid parts of ferrule members disposed upon the ends of the grip, said ferrule members being provided with boss portions arranged to curve over and thence to curve backwardly over the top of the arm portions to thereby afford a smooth protection for the user's hands and serving to keep them from contact with the ends of the arm portions of the shovel and to afford curved continuous surfaces at the exposed points of said ferrule.
2. A shovel handle assembly comprising a pair of spaced arm portions, a wooden grip portion, ferrules upon the ends of said grip portion, said ferrules having hollow bosses thereon constructed and arranged to form outwardly open vertical slots, open at the bottom to slidably receive the arm portions of the shovel handle, said bosses having vertically straight side portions to embrace the outer edges of the arm portions and prevent relative rotation of the handle and said ferrules.
3. A shovel handle assembly comprising a handle body portion and a grip assembly portion carried thereby, said grip assembly comprising a wooden grip, metallic ferrules upon the ends thereof and prevented from rotating with respect to the wooden grip portion, said ferrules having a semi-circular boss portion extending over and affording protection against contact with the upper ends of the arm portions of the handle, said ferrules further having flange portions to embrace the edges of the arm portions and prevent relative rotation of the grip assembly and the handle body portion when the parts are assembled together.
4. A shovel handle comprising a body portion having arm portions consisting of a re-

enforcing element, integral inner and outer sheet metal portions, the outer portions being folded over and embracing said reenforcing element, and a grip assembly carried by the body portion and comprising a wooden grip with metal ferrules thereon, said ferrules having a surface thereon arranged to directly abut against the inner surface of the inner wall portions of the arms, said ferrules further having portions thereof arranged to embrace the edges of the arms and prevent relative rotation of the grip assembly and the body portion of the handle.

5. A shovel handle comprising a pair of spaced sheet metal arm portions, a grip assembly carried thereby and therebetween, comprising a wooden grip, ferrules upon the ends thereof, said ferrules having substantially flat portions which abut the ends of the wooden grip inside the arm portions, said ferrules further having portions extending outwardly from the flat portion and forming outwardly open slots to receive the arms, said ferrules further having a boss portion thereon to afford a guard or shield for the terminating upper edges of the arm portions.

6. A ferrule construction for securing a wooden grip upon the arms of a shovel handle formed of sheet metal, said ferrule comprising an annular collar fitting over the edges of the wooden grip barb, means extending into the end of the wooden grip and a single curved fillet-like boss which extends from the annular collar and curves over thence backwardly to merge into a flat portion of the ferrule disposed upon the end of the grip inside the arm portions.

7. A ferrule for fastening a wooden grip to sheet metal arm portions of a shovel handle comprising a flat plate-like portion which abuts the end surface of the grip inside of the arms, and a boss portion struck outwardly from the flat portion at the edges to embrace the sides of the arms.

8. A ferrule for fastening a wooden grip to sheet metal arm portions of a shovel handle comprising a flat plate-like portion which abuts the end surface of the grip inside of the arms, and a boss portion struck outwardly from the flat portion at the top thereof forming a boss which affords protection to the user from the top of the arms.

9. A ferrule for fastening a wooden grip to sheet metal arm portions of a shovel handle comprising a flat plate-like portion which abuts the end surface of the grip inside of the arms, and a boss portion struck outwardly from the flat portion and thence curved over and back to merge with an annular shoulder extending over the edge of the wooden grip.

10. A shovel comprising a pair of spaced sheet metal arms, a wooden grip portion

carried thereby, and intermediate load imparting and protecting ferrules provided with a single continuous boss which curves over, protects and imparts force to the upper 5 edge of the arms and also extends downwardly at the sides of the arms to embrace the same for the purpose described.

11. A ferrule for a shovel handle with a flat base portion, an annular collar portion 10 and an intermediate boss portion extending semi-circularly about the top of the ferrule with integral depending portions which are substantially straight in contour upon their inner edges for the purpose described.

15. 12. A shovel handle comprising in combination, a wooden grip, ferrules upon the ends of said grip, said ferrules having an upper semi-circular boss provided with vertically depending flange portions which merge 20 with a smooth outer surface into the boss portion to afford a smooth outer surface for said ferrules, the interior of said flange portions being adapted to embrace the outer edges of the arm portions of the shovel 25 handle.

13. The invention set forth in claim 12,

in which the semi-circular boss portion is itself of hollow construction having a substantially semi-circular cross section.

14. A shovel handle comprising a pair of 30 spaced arm portions, a grip assembly carried thereby and therebetween, ferrules upon the end of said grip, said ferrules having a vertically slotted portion defined at the edges by a continuous boss portion which 35 embraces the edges of the arm portions of the handle and which extends over the top of the arm portions.

15. A shovel handle comprising a pair 40 of spaced arm portions, a grip assembly carried thereby and therebetween, comprising a wooden grip, ferrules upon the ends of said grip, said ferrules having vertically slotted portions defined at the edges by 45 boss portions which embrace the edges of the arm portions of the handle, said embracing boss portions being themselves hollow and having a substantially semi-circular central cross section.

In testimony whereof I hereto affix my 50 signature.

LEWIS E. WEBSTER.
